(57) **CLAIM**

The ornamental design for a quarter fender, as shown and described.

DESCRIPTION

FIG. 1 is a perspective view of a quarter fender showing our new design;

FIG. 2 is a left side view of the quarter fender shown in FIG. 1;

FIG. 3 is a rear view of the quarter fender shown in FIG. 1; FIG. 4 is a front view of the quarter fender shown in FIG. 1; and,

FIG. 5 is a top view of the quarter fender shown in FIG. 1. The broken lines shown in the figures represent portions of the quarter fender that form no part of the claimed design. FIGS. 1-5 illustrate our novel design for use on one side of a vehicle. Our novel design is also for use on the opposite side of a vehicle, which is mirror symmetrical to FIGS. 1-5 and therefore not separately illustrated.
